US00D882525S

(12) **United States Design Patent** (10) **Patent No.:** **US D882,525 S**
(45) **Date of Patent:** **** Apr. 28, 2020**

(54) **CONNECTOR TERMINAL**

- (71) Applicant: **Molex, LLC**, Lisle, IL (US)
- (72) Inventors: **Dwaraganathan Bhagynathan**,
Sathianathan, Lisle, IL (US); **Yves**
Lepottier, Lisle, IL (US)
- (73) Assignee: **Molex, LLC**, Lisle, IL (US)
- (**) Term: **15 Years**
- (21) Appl. No.: **29/635,361**
- (22) Filed: **Jan. 30, 2018**
- (51) LOC (12) Cl. **13-03**
- (52) U.S. Cl.
USPC **D13/154**
- (58) **Field of Classification Search**
USPC D13/154
CPC H01R 4/10; H01R 4/184; H01R 4/70
See application file for complete search history.

(57) **CLAIM**

The ornamental design for a connector terminal, as shown and described.

DESCRIPTION

FIG. 1 is a front perspective view of a connector terminal showing our new design;
FIG. 2 is a right side view thereof;
FIG. 3 is a left side view thereof;
FIG. 4 is a front view thereof;
FIG. 5 is a rear view thereof;
FIG. 6 is a top view thereof;
FIG. 7 is a bottom view thereof;
FIG. 8 is a rear perspective view thereof;
FIG. 9 is a front perspective view of an alternate embodiment of the connector terminal showing our new design;
FIG. 10 is a right side view thereof;
FIG. 11 is a left side view thereof;
FIG. 12 is a front view thereof;
FIG. 13 is a rear view thereof;
FIG. 14 is a top view thereof;
FIG. 15 is a bottom view thereof; and,
FIG. 16 is a rear perspective view thereof.

The broken lines showing the remainder of the connector terminal are for environmental purposes only and form no part of the claimed design.

1 Claim, 16 Drawing Sheets
